DESIGN FOR A GLOVE

Julius A. Higier, Gloversville, N. Y.

Application December 8, 1937, Serial No. 73,431

Term of patent 3½ years

To all whom it may concern:

Be it known that I, Julius A. Higier, a citizen of the United States of America, residing in Gloversville, in the county of Fulton and State of New York, have invented a new, original, and ornamental Design for a Glove, of which the following is a specification, reference being had to the accompanying drawing, forming part thereof, wherein,

The characteristic feature of my design resides in the particular arrangement of the contrasting flared center insertion in combination with the glove as shown.

I claim:

The ornamental design for a glove, substantially as shown and described.

JULIUS A. HIGIER.
